UNITED STATES PATENT OFFICE.

WILLIAM ALBRECHT, JR., OF LONG ISLAND CITY, NEW YORK, ASSIGNOR TO GEORGE R. SWART & COMPANY, INC., OF NEW YORK, N. Y., A CORPORATION OF NEW YORK.

SHEET FEEDER.

Application filed November 6, 1922. Serial No. 599,210.

My invention relates more particularly to certain novel improvements or attachments in sheet-feeding mechanism employing pneumatic means for automatically separating and feeding successive sheets of paper to printing, folding or ruling machines, or to other types of machines devised thereafter to operate on such sheets.

The objects of my invention are, among other things, to provide a novel form of control for the pneumatic suction mechanism to enable same to act intermittently in withdrawing and advancing the successive sheets in spaced relation to one another, which control may be either automatically or manually actuated, and may also be regulated and adjusted for properly spacing sheets of different sizes or lengths. Heretofore continuous front-edge sheet-feeders embodying a perforated suction feed-wheel for continuously feeding the sheets forwardly from either a vertical pile or a bank of fanned-out sheets have separated and advanced such sheets in a continuous forward flow with overlapping margins in that the rapidly revolving suction feed-wheel tends to pick up the front margin of the second sheet before the rear end of the preceding sheet is wholly disengaged from the periphery of the suction wheel. My improved attachment prevents this overlapping feeding of the sheets by automatically and intermittently cutting off the suction applied to the periphery of the feed-wheel in proper timed relation with the size or length of the sheets being fed, combined with an automatic control operable by a suitable caliper device to cut off the suction entirely whenever two or more sheets are fed through the feeding off rolls at the same time.

A further feature of my invention is to embody in such attachment a simplified and efficient mechanism which operates automatically to hold the valved cut-off in its open or inoperative position after such valve cut-off has been shifted either by the mechanism controlled by the caliper or by hand. And I have also provided means to disconnect my attachment from the feeding

devices proper so that the control of the suction cut-off is made altogether by the operator, combined with resetting means after the caliper device has operated to cut off the suction from the feed-wheel. 55

My improved sheet-feeder also embodies other features of novelty and improvement whereby the various operating mechanisms are simplified and made more effective and otherwise better adapted for use, all of 60 which will be hereinafter described and particularly pointed out in the appended claims.

The drawings show my improvements in a preferred form in a continuous sheet-feeder; however, such improvements are not 65 to be restricted to any particular type of sheet-feeder, since the inventions are adaptable to various forms of sheet-feeders with the same advantages and results.

Of the drawings, Fig. 1 is a front elevation of the feeder with my improved attachment shown as secured to the left side-frame thereof; 70

Fig. 2 is a side elevation of the feeder looking from the left in Fig. 1 and showing 75 the attachment in operative position with the suction ports closed;

Fig. 3 is an enlarged side elevation view showing the suction ports open;

Fig. 4 is a sectional view taken on the line 80 4-4 of Fig. 3 looking in the direction of the arrows;

Fig. 5 is a sectional view taken on the line 85 5-5 of Fig. 3 looking in the direction of the arrows;

Fig. 6 is a detailed side elevation showing the attachment disconnected and in inoperative position;

Fig. 7 is a detailed end view, partly in section, showing the position of the valved cut-off for the suction ports; and 90

Fig. 8 is an enlarged vertical sectional view of the caliper device shown in Figs. 1 and 2.

Similar numerals refer to similar parts 95 throughout the several figures.

Referring to the drawings, the left side-frame 9 is suitably supported on standards 10 and 10 (Fig. 2), and a similar side-frame 11 is on the right of the feeder but is not shown. 100

The sloping feed-board 11 is secured in the side frames over which board 11 the bank of fanned-out sheets (not shown) is advanced to the sheet-separating mechanism 5 by a series of spaced-apart carrier tapes 12 passing around pulleys 13 mounted on the shaft 14 journalled in the frames in the usual manner, only one of such tapes 12 and pulleys 13 being shown in Fig. 2.

10 In the present embodiment the sheet separating and feeding mechanism comprises a suction feed-wheel 15 (Fig. 1) the peripheral rim 16 of which is formed with a series of spaced-apart perforations 17 throughout, which wheel 15 is mounted on the shaft 18. The end of the shaft 18 is suitably journalled in the side-frame 9 as shown, and the wheel 15 is revolved by gear 19 secured to the shaft 18. The gear 19 15 enmeshes with the idler gear 20 which engages the gear 21 on the lower feed-roll shaft 22. The gear 21 enmeshes with the idler gear 23 which engages with the gear 24 on the power shaft 25 which is driven 20 from any suitable source of power not shown. The suction mouth-piece 26 rests on the inner face of the perforated rim 16, and is connected to the transverse suction tube 27 by the pipe 28 as shown in Fig. 1.

25 The required suction to operate the wheel 15 to enable it to pick up and separate the sheets on the feed-board 11 is applied to the tube 27 from the vertical pipe 29 connected with any suitable air-exhausting device not shown. Since these are common forms of printing machinery construction and are well-known in the art, they need not be more fully described, it being sufficient to note that the successive sheets are separated and 30 fed forward by the suction feed-wheel 15 as it revolves anti-clockwise (Fig. 2) to advance the sheets onto the lower feed-roll 30 mounted on the shaft 22, from which the sheets are thereafter carried forwardly by 35 any suitable conveyor mechanism not shown.

40 The means for automatically and intermittently controlling the suction on the periphery of the wheel 15 to regulate the feeding of the successive sheets by this wheel in suitable spaced relation to one another comprises the following mechanism: Adjustably mounted on the left end of the shaft 18 by set screw 31 (Fig. 4) is the collar 32 to which is secured the knurled disk 33 by 45 screws 34. Below the disk 33 is the rectangular plate 35 slidable vertically in the parallel tracks 36 and 37 secured to the frame 9 by screws 38 as shown in Figs. 2 and 3. Mounted in the upper portion of the plate 35 is the stub-shaft 39 which has the circular groove 40 formed therein (Figs. 4 and 5) by which the cam 41 is removably 50 mounted on the shaft 39 by the set-screw 42, the cam 41 being preferably formed with the integral sleeve 43 surrounding the shaft

39 as shown in Figs. 4 and 5. Mounted on the outer end of the sleeve 43 is the knurled wheel 44, which is held in position on the shaft 39 by the washer 45 and screw-nut 46 threaded in the end of the shaft 39. Pinned at 47 to the lower end of the plate 35 is the rod 48 slidably mounted in the bracket 49 affixed to the frame 9, and the compression spring 50 coiled about the rod 48 between the bottom of the plate 35 and bracket 49 55 acts to hold the wheel 44 in operative engagement with the disk 33 as shown in Fig. 3. To enable my attachment to accommodate sheets of different sizes or lengths, wheels 44 of different diameters are provided to vary the speed of rotation of the cam 41. Pivoted to the stub-shaft 51 in the frame 9 is the valve lever 52 to which are secured the valves 53 and 54 adapted to close and open the suction ports 55 and 56 respectively which are formed in the end of the tube 27 and in the upper portion of the pipe 29 respectively (Fig. 7). The structure and the mounting of these two valves 53 and 54 are the same, and is shown in detail in Fig. 5 with respect to valve 53.

The valve 53 carries the outwardly projecting stem 57 slidably mounted in the socket 58 formed in the lever 52 which also has an enlarged recess 59 to hold the compression spring 60 coiled about the stem 57 to enable the valve 53 to have a tight fit on the port 55 formed in the end of the tube 27. The valve 54 has the stem 61 (Fig. 3), and is similarly mounted in the lever 52 to open and close the port 56 formed in the pipe 29.

Pinned to the lever 52 at 62 is the arm 63 having the forked ends 64 and 65 above and below the inner end of the sleeve 43 as shown in Fig. 4. The washer 66 is arranged on the sleeve 43 between the forked ends 64 and 65 and the plate 35 as shown in Figs. 4 and 5. The pin 67 (Figs. 3 and 4) holds the knurled wheel 44 in rotary engagement with the cam 41. Pivoted at 68 to the arm 63 100 is the cam-roller 69 held against the cam 41 by the coil spring 70 detachably secured to the end of the lever 52 by the screw-pin 71; the opposite end of the spring 70 is pinned to the screw 72 as shown in Figs. 2, 3, and 6. The lower end of the rod 48 carries the catch-hook 73 adapted to engage the pin 74 mounted in the frame 9 to hold the plate 35 in its lowermost position as shown in Fig. 6 with the disk 33 and wheel 44 out of engagement. As the lever 52 oscillates on the shaft 51 under the action of the cam 41, the valves 53 and 54 open and close their respective suction ports 55 and 56, Fig. 2 showing the ports closed with the roller 69 in the drop of the cam 41, while Fig. 3 shows these ports open with the roller 69 bearing on the dwell of the cam 41.

To enable the valves 53 and 54 to open in order to thereafter cut off the suction auto-

matically from the feed-wheel 15 when two or more sheets are fed off by being stuck together or for any other reason, I have devised the following mechanism operable through any suitable caliper which is shown in Figs. 1, 2, 3, 6 and 8: The tie rods 75 and 76 support the bracket 77 to which is pinned the arm 78 in the outer end of which is affixed the stub-shaft 79 on which is journalled the upper feed roll 80 between which and the roll 30 the separated sheets are fed. The coil spring 81 connected to the shaft 79 and the tie-rod 76 holds the upper feed-roll 80 in yielding engagement with the lower feed-roll 30. Pivoted to the shaft 79 is the bracket 82 with the projecting lug 83. As shown in Fig. 8 the bracket 82 is formed to hold the threaded end of the stud 84 on which is journalled the sleeve 85 with a dividing flange 86 which separates the wheel 87 affixed to the outer end of the sleeve 85 from the disk-wheel 88 loosely mounted thereon with considerable "play" as shown. The outer wheel 87 is very slightly less in diameter than the disk-wheel 88 and is provided with a weighted portion 89 on one side thereof from which project two pins 90 and 91. This wheel 87 being loosely mounted on the stud 84 will be held by gravity against rotation.

Near the end of the lug 83 is the screw-pin 92 passing through a suitable aperture and screwed into the wing 93 projecting vertically from the arm 78, the pin 92 having a stop against which the lug 83 is yieldingly pressed by compression spring 94 coiled about the pin 92 as shown in Fig. 2. By this device the position of the disk wheel 88 relatively to the lower feed-roll 30 below same (Fig. 8) may be adjusted with a high degree of exactitude by turning the screw-pin 92.

Mounted on the transverse rock-shaft 95 is the collar 96 from which projects downwardly the curved arm 97 the free end of which is located in the path of movement of each of the two pins 90 and 91 as shown in Fig. 1. The left end of the shaft 95 carries outside the frame 9 the collar 98 from which depends the finger 99 adapted to engage the block 100 affixed to the rod 101 which is slidably horizontally through the bracket 102 secured to the frame. The collars 103 and 104 are adjustably secured to the rod 101 by set screws to limit the movement of the rod 101 and also the collar 104 adjustably locates the position of the block 100 on the rod 101 with reference to the finger 99.

Referring to Figs. 2 and 3, the rear end of the rod 101 is pivoted by the pin 105 to the plate 106 journalled on the stud 107; also journalled on the stud 107 is the weighted pawl 108 the nose of which is adapted to engage the notch 109 cut in the valve lever

52. The pin 110 in the plate 106 holds the pawl 108 out of engagement when the suction ports 55 and 56 are closed as shown in Fig. 2, but when the plate 106 is rocked to the left by the rod 101, the nose of the pawl 108 falls into the notch 109 when the lever 52 is moved to the position shown in Fig. 3 by the action of the cam 41 with the suction ports 55 and 56 opened. As shown in Figs. 1 and 2, the shaft 95 also has secured thereto the resetting lever 111.

The very slight difference in the diameters of the wheels 87 and 88 is approximately that of the thickness of a sheet from stock of average weight, and the ratio of effective diameters may be slightly varied and adjusted to a great degree of nicety by means of screw-pin 92, the loose bearings of the wheel 88 allowing it to rest by gravity on the lower feed-roll 30 while the wheel 87 is slightly raised or lowered with relation to roll 30. This adjustment is made so that a single sheet of paper will pass under the wheel 88 and also under the weighted wheel 87, but not contacting with the latter with sufficient pressure to cause it to revolve against the action of the weighted portion 89. However, should two or more sheets pass at the same time under wheels 87 and 88, the increased thickness of same will be sufficient to cause frictional engagement of the wheel 87 and its rotation against the action of the weighted portion 89 so as to cause the pins 90 and 91 to strike successively the curved arm 97 and rock same rearwardly or in a clockwise direction (Fig. 2). Thereupon the shaft 95 is rocked to swing the finger 99 and rod 101 to the left to release the weighted pawl 108 as held as shown in Fig. 2 so that the latter will engage the notch 109 in the lever 52 when the cam 41 has moved the lever 52 to the position shown in Fig. 3. The handle 112 on the forward end of the rod 101 enables the operator to move the rod 101 to the left at will to shift the plate 106 to release the pawl 108 as has been hereinbefore described.

Referring to Fig. 6, in which I have shown the disk 33 and wheel 44 out of engagement with the catch-hook 73 fast to the pin 74 and the spring 70 disconnected from the pin 71. I have provided a link 113 which is removably secured to the pin 105 and also to the pin 114 on the valve lever 52 to operatively connect the rod 101 to the lever 52 so that the operator may open and close the suction ports 55 and 56 at will and independently of the mechanisms shown and described to actuate same through the continued operation of the feeder.

The operation of my sheet-feeder is substantially as follows. When the suction feed-wheel 15 is rotating in an anti-clockwise direction (Fig. 2) to feed off the separate sheets from the bank of sheets on the feed-board 11

and carrier tapes 12 between the feed-rolls 30 and 80, the suction is intermittently applied to the perforated rim by the coaction of the disk 33 on the shaft 18 with the knurled wheel 44 journaled on the vertically adjustable plate 35, the wheel 44 causing the cam 41 rotating in unison therewith to oscillate the valved lever 52 to actuate in turn the valves 53 and 54, over the suction ports 55 and 56 respectively to "make" or "break" the suction in the mouth-piece 26 which rides on the inner face of the perforated rim 16, the opening of the suction ports to atmosphere equalizing the air pressure on either side of the rim 16 to prevent the wheel 15 picking up a sheet. The action is suitably timed by use of knurled wheel 44 of various diameters so that the suction ports 55 and 56 are opened (Fig. 3) when the perforations 17 registering with the mouth-piece 26 are passing over the rear ends of the sheets, and such suction ports remain open sufficiently to allow a suitable spacing between the tail end of the first sheet which is now advanced between the feed-rolls 30 and 80 and the front edge of the second sheet. When the ports 55 and 56 are closed, the mouth-piece 26 is again in direct connection with the air-exhausting device, and the wheel 15 picks up the front edge of the second sheet.

By this mechanism the suction acts intermittently through the wheel 15 to properly space the successive sheets, and the rapidity of the oscillations of the lever 52 may be varied according to the requirements for sheets of various sizes or lengths, by replacing the knurled wheel 44 with a like wheel of larger or smaller diameter. For this purpose a set of knurled wheels 44 of different diameters are preferably provided to take care of the feeding of sheets of different lengths.

The operation of the caliper device to control the position of the weighted pawl 108 has been heretofore described and it will be observed that as the caliper mechanism acts when two or more sheets are fed as a unit to move the rod 101 to the left, the pawl 108 automatically swings clockwise ready to engage the notch 109 in the lever 52 to hold same in the position shown in Fig. 3 as soon thereafter as the cam-roller 69 rides up on the high part of the cam 41 to throw the lever 52 to the left. Again the pressman may shift the rod 101 at will either to allow the pawl 108 to swing into operative position or to draw same away from the lever 52 into the inoperative position illustrated in Figs. 2 and 6. By means of the hand-lever 111 the pressman rocks the shaft 95 so as to bring the arm 97 again into the path of movement of the pins 90 and 91.

The foregoing constructions embody the principles of my invention, but various changes may be made in the structural details

without departing from the scope of my improvements. However, the foregoing is sufficient to disclose the underlying principles and advantages as applied to a continuous sheet-feeder.

70

I claim as my invention:

1. In a sheet-feeder, a rotary suction feed-wheel operating on a stack of superposed sheets to separate and advance the successive sheets, selective interchangeable rotary members of different peripheries detachably connected with, but directly actuated by, said feed-wheel, a cam mounted concentrically, and having a detachable operative connection, with any of said members to rotate said cam at a correspondingly selective speed, and a valve actuated and controlled by said cam to intermit at a predetermined point in each sheet cycle the suction applied to said feed-wheel.

75

2. In a sheet-feeder, a rotary suction feed-wheel operating on a stack of superposed sheets to separate and advance the successive sheets, selective interchangeable rotary members of different peripheries detachably connected with, but directly actuated by, said feed-wheel, a cam mounted concentrically, and having a pin and slot operative connection, with any of said members to rotate said cam at a correspondingly selective speed, and a rock-lever directly actuated and controlled by said cam, and a valve on said rock-lever to intermit at a predetermined point in each sheet cycle the suction applied to said feed-wheel.

80

3. In a sheet-feeder, a rotary suction feed-wheel operating on a stack of superposed sheets to separate and advance the successive sheets, selective interchangeable rotary members of different peripheries detachably connected with, but directly actuated by, said feed-wheel, a cam mounted concentrically, and having a detachable operative connection, with any of said members to rotate said cam at a correspondingly selective speed, and a pair of coating valves both actuated and controlled by said cam to intermit at a predetermined point in each sheet cycle the suction applied to said feed-wheel through the continued movement of the feeder.

85

4. In a sheet-feeder, a rotary suction feed-wheel operating on a stack of superposed sheets to separate and advance the successive sheets, selective interchangeable rotary members of different peripheries detachably connected with, but directly actuated by, said feed-wheel, a cam mounted concentrically, and having a pin and slot operative connection, with any of said members to rotate said cam at a correspondingly selective speed, and a rock-lever directly actuated and controlled by said cam, and a pair of coating valves on said rock-lever to intermit at a predetermined point in each

sheet cycle the suction applied to said feed-wheel through the continued movement of the feeder.

5. In a sheet-feeder, rotary suction-feeding devices operating on a stack of superposed sheets to separate the successive sheets, means actuated and controlled by said feeding devices to intermit in each cycle the suction applied thereto, and manual means to separate said last-mentioned means from operative relation with said feeding-devices.

6. In a sheet-feeder, rotary suction-feeding devices operating on a stack of superposed sheets to separate the successive sheets, means actuated and predeterminedly controlled by the revolution of said feeding

devices to intermit in each sheet cycle the suction applied thereto, means to separate said last-mentioned means from operative 20 relation with said feeding-devices, and means to hold said first-mentioned means in inoperative position.

7. In a sheet-feeder, a constantly rotating suction feed-wheel operating on a stack of 25 superposed sheets to successively separate and advance same, means operable through the continued movement of the feeder and moving in unison with said feed-wheel and controlled by the extent of its revolution to 30 intermit the suction applied to said wheel, and means to separate said means from operative relation with said feed-wheel.

WILLIAM ALBRECHT, JR.
